PROCESS OF COOLING GASES

Hans Baehr and Karl Braus, Leuna, Germany,
assignors to I. G. Farbenindustrie Aktien-
gesellschaft, Frankfort-on-the-Main, Germany

Application January 16, 1937, Serial No. 120,911
In Germany January 24, 1938

5 Claims. (Cl. 62—176)

The present invention relates to a process of cooling gases.

A method frequently used to cool hot gases or vapors consists in causing atomized water or another liquid to evaporate in the gases. This method of working succeeds with comparative easiness if the cooling temperature to be attained lies considerably above the boiling point of the evaporating agent. Difficulties, however, arise when the gases have to be cooled down to a temperature which is near the boiling temperature of the injected cooling agent, for example when hot gases are, by means of injected water, to be brought to a temperature of 150° C. Even if the water be most finely atomized by means of appropriate nozzles and large evaporation spaces be provided, it is no longer possible to evaporate the water completely when approaching said low temperature. In these cases it is necessary to employ a large excess of water, the non-vaporized portion there being collected and removed. The difficulties involved with the said cooling method are such as to exclude the use of the simple injection method for the cooling of gases in many cases which has therefore to be done by complicated indirect processes. For example, if the gases to be cooled contain constituents which are liable, in the presence of liquid water, to attack the structural materials of the apparatus, as is the case for example with gases obtained by roasting pyrites, care must be taken that no liquid water separates at any place of the apparatus as otherwise the structural materials would be destroyed. The injection water also, if introduced between two superimposed contact layers, must be completely evaporated, also in view of the fact that it would otherwise hit the lowermost layer and damage the same. The separation of liquid water must finally be avoided in all cases where products are to be recovered from the gases at the desired cooling temperature which products would solidify at still lower temperatures, as for example at 100° C., and then clog the separator.

We have now found that the liquids used for cooling gases or vapors or mixtures thereof by the injection method can be rapidly and completely vaporized if the same (preferably water) have a boiling temperature under the actual gas pressures below the gas temperature to be obtained by the cooling, and are released from pressure while in a finely distributed state, into the medium to be cooled at a temperature above their boiling temperature under the pressure of the gases to be cooled but below the temperature of

In order to atomize the injection liquid which is usually done by forcing it through narrow nozzles, it must be subjected to an elevated pressure, and therefore it is possible in general to heat the liquid, as for example water, to temperatures above the boiling point corresponding to the pressure of the gas. Where injection nozzles are used, the water supply conduit of which is under no or only too small a superatmospheric pressure, the necessary pressure must be produced by the arrangement directly in front of the nozzles of a throttling valve or another throttle.

The water may be heated in any appropriate manner, i. e. either indirectly by means of steam or flue gases or directly by leading steam into the water contained in a suitable mixing device. If the injection is to be performed within the reach of a boiler, the superheated pressure water wanted is generally available in the form of the feed water or the boiler water itself. When special heating devices are used, these are preferably arranged close to the place where the injection is performed, to avoid any loss in temperature after superheating as much as possible.

When cooling gases or vapors under ordinary pressure it is usually sufficient that the water to be vaporized supplied to the injection nozzles has a temperature above 100° C., preferably at least 105° C., to 130° C. Whereas higher temperatures merely require somewhat larger amounts of water to be vaporized, the lowering of the temperature to below the boiling temperature of the injection water immediately effects such a slackening of the speed of evaporation that it is no longer possible to cool the gases to low temperatures, more particularly below 200° C.

If the gases to be cooled are under pressure, higher temperatures of the water must be maintained in accordance with the pressure of the gas. On the other hand, however, when cooling gases under a pressure inferior to atmospheric pressure water temperatures of less than 100° C. may be used. In each case the temperature of the liquid under pressure should be some degrees centigrade above the boiling point at the actual gas pressure; preferably this difference should at the least be about 5° C.

The present invention is not restricted to the use of water, but it is practicable quite generally in the case of any liquids which are vaporized in gases or vapors for the purpose of cooling gases and do not exert any other undesired influence on these gases.

In carrying out the process according to this

invention it is advantageous to assist the vaporization for example by using atomizing nozzles producing the finest possible degree of atomization, arranging a plurality of nozzles, atomizing towards various directions within the vaporizer or other well known means.

The affixed drawing is a diagrammatic illustration of an apparatus wherein the present process may be carried out.

10 Referring to this drawing, the hot gases enter cooling chamber 1 through opening 2 and leave through exit 3. Pipe 4, located in the upper part of cooling chamber 1, is provided with spraying nozzles 5. Pump 6 is used to build up the pressure of the cooling medium, which flows through pipe 7, into and through heater 8, and from there to cooling chamber 1 through pipe 10. Steam enters heater 8 through pipe 9 and the resulting condensate leaves the heater through pipe 11. 15 Thus, for instance, if hot gases entering opening 2 at a temperature of 400° C. are to leave cooling chamber 1 at a temperature of 150° C. and pump 6 is adjusted so as to maintain a water pressure of about 10 atmospheres in the pipe line, the 20 quantity of steam entering heater 8 is regulated so that the water passing through heater 8 will leave the heater at a temperature of 140° C. When this water is forced through spraying nozzles 5 in cooling chamber 1, it is so quickly 25 and completely vaporized that no water is collected at the bottom 12 of the chamber and that no droplets of water are carried out with the gases which have been cooled to 150° C.

The process will be used with advantage in any 30 case where gases and vapors shall rapidly and within a narrow space be cooled down to low temperatures without any separation of the injected liquid. It is excellently adapted for use in exothermic catalytic reactions, in which the main 35 part of the gases or vapors involved is converted by means of a first contact layer, whereas the final conversion is effected by means of a second contact layer and in which the gases or vapors are cooled between the said two stages. Processes 40 of the said kind are applied for example for producing hydrogen and carbon monoxide from hydrocarbons and steam or for oxidizing sulphur dioxide to sulphur trioxide, in the synthesis of ammonia from nitrogen and hydrogen, liquefied 45 ammonia being preferably injected in this case between the contact layers for cooling the gas, or in the synthesis of hydrocarbons from carbon monoxide and hydrogen, superheated hydrocarbons being preferably injected in this latter case 50 between several contact layers. The process is valuable also when products formed are to be precluded from decomposition by cooling them rapidly, as for example in the production of nitrogen oxides by combustion of ammonia. In the 55 production of unsaturated hydrocarbons by thermal decomposition and other cases. A special importance of this process resides in the possibility of cooling such gases by the injection of water which, as for example gases obtained by roasting 60 pyrites contain substances which are aggressive in the presence of water and with which the formation of liquid water must therefore be carefully avoided.

The speed of evaporation of the water in the 65 said method of working is so high that the process is even applicable for cooling gas mixtures which, as for example the sulphur containing gases obtained by the well known Claus process, consist of substances, in the latter case of sulphur, 70 which would immediately solidify when cold

water would be injected. Said Claus process comprises the catalytic oxidation of hydrogen sulfide at high temperatures with air according to the equation

and thereby gives rise to gases of relatively high temperatures between about 200° and 500° C. which contain substantial quantities of elemental sulfur. When cooling these gases in accordance with the present invention, there is no danger of solidifying the sulfur as has heretofore been the case. The present process is, therefore, of great advantage for use in the production of sulfur by the Claus process and its modifications.

The present invention, however, is not confined to the cooling down to low temperatures alone. It may be employed with the same result in order to obtain any desired gas temperature. For example, if the injected water or other liquid would be vaporized at higher temperatures also without being superheated, the superheating accelerates the vaporization to such an extent that the dimensions of the vaporizers may be strongly reduced and considerable savings in apparatus 25 may be realized.

The following example serves to illustrate how the present invention may be carried out in practice, but the invention is not restricted to this example.

Example

10,000 cubic meters per hour of Claus furnace contact gases having a temperature of 400° C. and containing 110 grams of sulphur per cubic meter (measured at 400° C.) are to be cooled 35 down to 150° C. for the purpose of converting the gaseous sulphur into the liquid phase in order to separate it. The said gases are led downwards through a cylindrical vaporizer having 3 meters in diameter and 4 meters in height. At the top 40 of the vaporizer 3 water supply pipes are introduced radially and in a symmetrical order. Each of the said pipes which extend nearly to the center of the vaporizer, has screwed on thereto at equal intervals 6 atomizer nozzles with a spraying aperture of 0.9 millimeter width, the said nozzles being so arranged in a downward direction that their central lines deviate from the vertical direction by an angle of 30° either to the right or to the left. Before their arrangement 45 all of the nozzles are carefully adjusted so as to ensure the finest possible atomization of the water. Through the said nozzles 900 liters of water are injected per hour into the vaporizer 50 with a temperature of about 125° C. 55

The injected water is completely vaporized in the vaporizing space. The gases leaving the vaporizer at the bottom above the vaporizer sump are cooled down to 150° C., the whole of the sulphur which was previously in the gaseous state 60 being condensed into the liquid phase. One third of the sulphur precipitates as a liquid in the vaporizer sump and is continuously withdrawn therefrom by means of a heated overflow pipe; the bulk of the sulphur is practically completely 65 separated on an electro-filter arranged behind the cooler.

If the injection water is atomized at a temperature of 90° instead of 125° C. the other conditions remaining unchanged, the gases leaving the 70 vaporizer still have a temperature of 250° C., so that a considerable part of the sulphur remains in the gaseous phase and cannot be completely recovered by means of the electro-filter. Moreover, the water which has not been vaporized col- 75

lects in the vaporizer sump and there causes the sulphur to solidify which in turn leads to incrustations and stoppages, so that neither the complete recovery of the sulphur nor a regular 5 operation is possible.

What we claim is:

1. A process of cooling a hot gaseous medium by injecting and evaporating a liquid therein comprising injecting the said liquid in a finely 10 distributed state and at a temperature above its boiling temperature corresponding to the pressure of the gaseous medium to be cooled and below the temperature of the said gaseous medium, the quantity of said liquid being so limited 15 that the liquid is completely evaporated.
2. A process of cooling a hot gaseous medium by injecting and evaporating water therein comprising injecting the said water in a finely distributed state and at a temperature above its 20 boiling temperature corresponding to the pressure of the gaseous medium to be cooled and below the temperature of the said medium, the quantity of said water being so limited that the water is completely evaporated.
- 25 3. A process of cooling a hot gaseous medium by injecting and evaporating water therein comprising injecting the said water in a finely dis-

tributed state and at a temperature which is at least about 5° C. above its boiling temperature at the pressure of the medium to be cooled and below the temperature of the said medium, the quantity of said water being so limited that the water is 5 completely evaporated.

4. A process of cooling a hot gaseous medium under atmospheric pressure and having a temperature between about 200° C. and 500° C., by injecting and evaporating water therein comprising 10 injecting the said water in a finely distributed state and at a temperature between about 105° and 130° C., the quantity of said water being so limited that the water is completely evaporated.

5. A process of cooling hot gases under atmospheric pressure obtained by the well known Claus process and its modifications, having a temperature between about 200° and 500° C. and containing substantial amounts of elementary sulphur 15 by injecting and evaporating water therein comprising injecting the said water in a finely distributed state and at a temperature of about 125° C., the quantity of said water being so limited that the water is completely evaporated.
